ROLLER UNIT FOR WINDOW STRUCTURES

Original Filed Aug. 3, 1928

UNITED STATES PATENT OFFICE

EMIL WILKING, OF CHICAGO, ILLINOIS

ROLLER UNIT FOR WINDOW STRUCTURES

Original application filed August 3, 1928, Serial No. 297,366. Divided and this application filed September 17, 1930. Serial No. 482,399.

The present invention relates generally to roller units for use in connection with window structures. More particularly, the invention relates to that type of unit which comprises (1) a spring-actuated roller which is adapted to be mounted on a window frame of standard construction in close proximity to one of the end or crossbars thereof, and (2) a fabric dust arresting screen which is wound around and anchored to the roller and is connected at its outer or distal end to one of the vertically movable panels in the window frame so that it will be unwound automatically and will bridge or close the window opening when the panel is shifted into any of its opened positions.

One object of the invention is to provide a roller unit of this type in which the fabric screen is provided at its inner end with an elongated transversely extending metallic stay and is connected detachably to the roller by means of latches which are pivotally mounted on the ends of the spring-actuated roller and are shiftable into locked relation with the ends of the stay.

Another object of the invention is to provide a roller unit of the character hereunder consideration in which the stay at the inner end of the fabric screen is provided along one of the side margins thereof with an integral inwardly extending flange which is adapted to interlock with a longitudinal groove in the periphery of the roller and serves to hold the stay against circumferential displacement with respect to the roller.

A further object of the invention is to provide a roller unit for window structures which is generally of new and improved construction and may be manufactured at a comparatively low cost by virtue of the fact that it consists of but a comparatively small number of parts.

Other objects of the invention and the various advantages and characteristics of the present roller unit construction will be apparent to those skilled in the art from a consideration of the following detailed description.

The invention consists in the several novel features which are hereinafter set forth and

are more particularly defined by claims at the conclusion hereof.

In the drawing which accompanies and forms a part of this specification or disclosure and in which like numerals of reference denote corresponding parts throughout the several views:

Figure 1 is a front elevational view of a window structure in which the lower panel is associated with a roller unit embodying the invention;

Figure 2 is a fragmentary perspective of the fabric screen and the spring-actuated roller, exhibiting in detail the manner in which the latches at the ends of the roller cooperate with the ends of the stay to secure the inner end of the screen in connected relation with the roller;

Figure 3 is a perspective of the roller;

Figure 4 is a perspective of the stay which is attached to the inner end of the fabric screen and operates in conjunction with the latches to connect the screen detachably to the roller;

Figure 5 is a perspective of the fabric screen; and

Figure 6 is a side view of one of the latches on the roller.

The roller unit which forms the subject matter of the invention comprises a flexible screen 7 and a roller 8 and is designed primarily for use in connection with a window structure W. The latter, as illustrated in Figure 1 of the drawing, is of the type or character that is generally employed and used in connection with buildings, dwellings and like establishments, and embodies an inner panel a and an outer panel b. These panels are mounted in a rectangular frame C so that they are offset laterally with respect to one another and are shiftable vertically into overlapping relation to uncover the upper and lower parts of the window opening. The panel a is adapted normally to cover the lower half of the winding opening and consists of a pane a' of glass or similar transparent material and a rectangular sash or casement a² in which the pane a' is mounted and held in place by any suitable sealing means. The sash a² embodies a bottom cross-

bar a^3 and is guided by strips c' on the side bars of the window frame so that it may be raised by vertical shift movement into any of its various open positions. The panel a is 5 counterbalanced so that it will remain in place by means of a pair of weights a^4 which are disposed in compartment at the sides of the frame c and are connected to the upper corners of the sash by cables a^5 . Handles a^6 10 for use in raising and lowering the panel a are secured to the inner face of the bottom crossbar a^3 . The outer panel b is similar in construction to the inner panel and is adapted normally to cover the upper half of the window opening.

The roller 8 is located in close proximity to the bottom crossbar of the window frame and has the flexible screen 7 wound therearound. The outer or distal end of the 20 screen is detachably connected in any suitable manner to the crossbar a^3 of the sash a^2 so that it will be unwound and will bridge or close the window opening when the panel a is lifted into any of its raised positions. 25 The screen 7 is preferably formed of loosely woven fabric and serves, when in its bridged or operative position, to arrest dust particles. It is preferably of such width that the side margins thereof extend substantially to the side bars of the window frame c . The roller 8 is substantially cylindrical in conformation and, as previously pointed out, is mounted in close proximity to the bottom bar of the window frame c . It is slightly 30 wider than the screen and is actuated or rotated by a helical spring 9 so that it automatically winds the screen thereon when the panel a is lowered into its closed position. Brackets 10 and 11 serve to hold the roller in 35 place. These brackets fit against the lower ends of the side bars of the window frame and are arranged so that the lower edges or margins thereof abut against the bottom crossbar of said frame. Screws or similar attaching devices (not shown) are utilized to secure the 40 brackets in place. The bracket 10 has punched therein an inwardly projecting portion 12 having a circular opening (not shown) in which is journalled a pivot pin 13 at one end of the roller. This pin is fixed to the head 14 of a sheet metal cap 15. The latter embodies a cylindrical skirt 16 which forms a socket into which said one end of the roller 8 fits. Two or more screws 17 extend 45 through the skirt and operate to hold the cap securely in place. The other end of the spring-actuated roller 8 is provided with a sheet metal cap 19 which is similar in construction to the cap 15 and comprises a head 50 20, and a cylindrical skirt 21. The cap is rigidly connected to the roller by screws 22 which extend through the skirt 21 and into the contiguous end of the roller. The actuating spring 9 is disposed in a longitudinal 55 chamber 23 which is formed in the central

portion of the roller. The spring extends throughout this chamber and the end thereof which is disposed adjacent to the cap 15 is suitably anchored. The other end of the spring is secured to the inner end of a polygonal lock bar 24. This bar is rotatably mounted in the cap 19 and the outer end thereof is positioned in a slot (not shown) which is formed in an instruck portion 25 on the bracket 11. The aforesaid slot is 75 shaped so as to hold the bar against rotation when it is in its operative position. By so arranging the bar it is manifest that any rotation of the roller 8 resulting from unwinding of the screen 7 causes the spring 9 to be 80 placed under tension. When the panel a is raised the flexible screen 7 will be unwound from the roller and will cause the latter to rotate in a direction which results in winding of the spring. When the panel is lowered the 85 spring causes rotation of the roller in the opposite direction and automatically winds the screen back in place. A characteristic and an advantage of utilizing a screen and roller of this type is that the ordinary wire screen 90 panel which obstructs or interferes with clear vision through the windows may be dispensed with.

The inner end of the screen 7 is secured or anchored to the roller 8 by an elongated metallic stay 26. This stay is removably held in a hem 27 which is formed by doubling over the inner end of the screen and securing it in place by stitching 28. The ends of the stay 26 project outwardly beyond the ends 95 of the hem to form tongues 29. These tongues overlap the skirt portions of the sheet metal caps 15 and 19 and are releasably held in place against radial displacement by a pair of latches which are pivotally connected to the heads of said caps. The latches are 100 formed of sheet metal and each comprises a pivot member 31 and a latch member 32 which extends at right angles to the pivot member and overlies the contiguous tongue 105 29. The members 32 of the latches have abutments or stops 33 at one end thereof. These stops are adapted to engage the side edges of the tongues 29 so that the latches will not 110 rotate out of engagement with the tongues when they are once shifted into place. The other ends of the latch members 32 are bent radially or outwardly to form fingers 34 for use in rotating the latches into their operative position. The stay 26 is curved so as 115 to fit properly against the periphery of the roller 8 and one side margin thereof is bent downwardly so as to form a flange 35 which fits into a longitudinal groove 36 in the roller. This flange and groove form an interlocking 120 connection between the stay and roller which prevents relative rotative movement. A characteristic and an advantage of utilizing the latches is that the stay is held in place so it 125 may be readily released whenever it is desired 130

to remove the screen from the roller for repair or replacement purposes.

In assembling the screen with respect to the spring-actuated roller, the stay 26 is first inserted into the hem 27. Thereafter the stay is placed against the periphery of the roller in such a manner that the flange 35 is interlocked with the groove 36. Upon placement of the stay against the roller, the latches are swung so that the members 32 overlie the tongues 29 on the ends of the stay and thus lock the stay releasably in place. In swinging the latches into place, the stops 33 serve to prevent overthrow of the latches.

When the screen becomes dirty or needs to be replaced, it is only necessary to unwind the screen and then release the latches so as to free the stay with respect to the roller.

The herein disclosed roller unit is exceedingly simple as far as construction is concerned and may be manufactured at a comparatively low cost by virtue of the fact that it embodies but a small number of parts. By utilizing the latches as the instrumentality whereby the stay at the inner end of the screen is held in place, provision is made for readily releasing the screen from the roller when desired. If desired, the unit may be mounted adjacent the top crossbar of the window frame and used with the outer panel *b*.

Whereas the unit has been described as a dust arrester and as embodying a loosely woven flexible screen, it is to be understood that the unit may be used for other purposes and that a shade may be employed instead of the screen. It is also to be understood that the invention is not restricted to the details set forth, since these may be modified within the scope of the appended claims, without departing from the spirit and scope of the invention.

This application is a division of an application filed by me August 3, 1928, Serial No. 297,366 patented Jan. 13, 1931, No. 1,783,757.

Having thus described the invention, what I claim as new and desire to secure by Letters Patent, is:

1. A unit for use in connection with a structure such as a window frame, comprising a spring-actuated roller for supporting therearound a flexible element, a stay attached to the inner end of the element and adapted to be placed longitudinally against the roller, and means for detachably connecting the inner end of the element to the roller, embodying a latch mounted movably on one end of the roller and shiftable into and out of locked relation with the contiguous end of the stay.

2. A unit for use in connection with a structure such as a window frame, comprising a spring-actuated roller for supporting therearound a flexible element, a stay attached to the inner end of the element and

adapted to be placed longitudinally against the roller, and means for detachably connecting the inner end of the element to the roller, embodying a latch mounted pivotally on one end of the roller and shiftable into and out of locked relation with the contiguous end of the stay. 76

3. A unit for use in connection with a structure such as a window frame, comprising a spring actuated roller for supporting therearound a flexible element, a stay attached to the inner end of the element and adapted to be placed longitudinally against the roller, means for connecting detachably said inner end of the element to the roller, embodying a latch connected pivotally to one end of the roller and shiftable into and out of locked relation with the contiguous end of the stay, and means for preventing overthrow of the latch when it is shifted into its locked position. 80

4. A unit for use in connection with a structure such as a window frame, comprising a spring actuated roller for supporting therearound a flexible element, a stay attached to the inner end of the element and adapted to be placed longitudinally against the roller, means for connecting detachably said inner end of the element to the roller, embodying a latch connected pivotally to one end of the roller and shiftable into and out of locked relation with the contiguous end of the stay, and means for preventing overthrow of the latch when it is shifted into its locked position. 85

5. A unit for use in connection with a structure such as a window frame, comprising a spring-actuated roller for supporting therearound a flexible element, a stay attached to the inner end of the element and adapted to be placed longitudinally against the roller, means for connecting detachably

90

95

one end of the roller and shiftable into and out of locked relation with the contiguous end of the stay, and means connected to the latch for preventing overthrow of the latter when it is shifted into its locked position. 100

shiftable into and out of locked relation with the stay.

7. A unit for use in connection with a structure such as a window frame, comprising a spring-actuated roller for supporting therearound a flexible element, a stay attached to the inner end of the element and adapted to be placed longitudinally against the roller, and latches for detachably connecting the inner end of the element to the roller, mounted movably on the ends of said roller and shiftable into and out of locked relation with the ends of the stay.

8. A unit for use in connection with a structure such as a window frame, comprising a spring-actuated roller for supporting therearound a flexible element, a stay attached to the inner end of the element and adapted to be placed longitudinally against the roller, and latches for detachably connecting the inner end of the element to the roller, mounted pivotally on the ends of said roller and shiftable into and out of locked relation with the ends of the stay.

25 9. A unit for use in connection with a structure such as a window frame, comprising a spring-actuated roller for supporting therearound a flexible element, caps at the ends of the roller having formed therein 30 sockets in which the roller ends fit, a stay attached to the inner end of the element and adapted to be placed longitudinally against the roller, and means for detachably connecting said inner end of the element to the 35 roller, embodying members formed separately from and mounted movably on the caps and adapted to cooperate with the ends of the stay.

Signed at Chicago, Illinois, this 13th day
40 of September, 1930.

EMIL WILKING.
